UNITED STATES PATENT OFFICE.

MICHAEL BOYTON, OF HOBOKEN, NEW JERSEY.

WRENCH.

No. 850,900.

Specification of Letters Patent.

Patented April 23, 1907.

Application filed June 5, 1906. Serial No. 320,319.

To all whom it may concern:

Be it known that I, MICHAEL BOYTON, a citizen of the United States, residing at Hoboken, in the county of Hudson, State of New Jersey, have invented certain new and useful Improvements in Wrenches; and I do hereby declare the following to be a full, clear, and exact description of the invention, such as will enable others skilled in the art to which it appertains to make and use the same.

This invention has relation to pipe-wrenches.

It is well understood that in pipe-wrenches it is necessary to secure such a firm hold upon the pipe operated upon that it can be turned or screwed up and at the same time the action must be such as to rotate the pipe and not to crush it between the jaws. Again, the wrench must be so constructed that a reverse movement of the handle will cause the jaws to "let go" the pipe and not to hold on to it.

It is the object of the present invention to provide improvements in a pipe-wrench whereby the jaws may be set on the pipe so as not to slip thereon in the work of turning it "up" and to let go the instant the handle of the wrench is moved in the opposite direction.

To the foregoing ends my invention consists of the improvements which I will now proceed to describe in detail in connection with the annexed drawings, forming a part of this specification, and then point out with particularity in the subjoined claims.

Of the said drawings, Figure 1 is a side elevation of my improved pipe-wrench. Fig. 2 is a longitudinal section. Fig. 3 is an edge view. Fig. 4 is a transverse section.

Similar figures of reference designate similar parts or features, as the case may be, wherever they occur.

In the drawings, 10 designates the ratchet-bar provided on its outer face with ratchet-teeth 11, and 12 is the guide-bar, at one end of which bars is the fixed jaw 13, which is preferably case-hardened. To a certain extent the two bars mentioned perform the functions of a handle in connection with the handle proper, 14, and in addition to special functions mentioned in connection therewith in the following description. 15 is the sliding or adjustable jaw removably secured in the seat formed in the forward face of the slide 16, adapted to be moved longitudinally on the ratchet and guide-bars 10 and 12. A

portion of the said slide is made hollow and is provided inside with a pivoted dog 17, that is adapted to engage the teeth 11 of the ratchet-bar and carries a light spring 18, that operates normally to bear the dog away from the teeth. Extensions 19, forming a part of the slide, project on opposite sides of the bars 10 and 12 and are provided with holes in which a pivot-pin 20 may extend to pivot the inner end of the screw-rod 21 of the handle 14 thereto. The said inner end of the screw-rod is constructed to fit between the said extensions 19 and move in the space 22 between the said bars. The removable jaw 15, as well as the dog 17, being capable of easy renewal, if need be, may be tool tempered or hardened, and this may be done with other parts of the wrench, if deemed desirable.

The screw-rod 21 is threaded from near its head to its opposite end.

At the ends of the members or bars 10 and 12 opposite to the fixed jaw is a fixed collar 22^a, which loosely receives one end portion 80 of the handle proper, 14. A shoulder 22' is formed upon the member 14 and bears against the outer end face of the collar, and a nut 23, engaged with the threaded extremity of the handle proper between the bars 10 and 12, 85 bears against the inner end face of the collar. A set-screw 23' is provided for holding the nut normally against movement.

The thread of the rod 21 is a left-hand thread, and the handle proper, 14, which is 90 tubular, is provided with an internal left-hand thread, so that when the handle proper is turned to the left the rod 21 will be turned into it, and when it is turned to the right it will be forced from it.

With the above-described construction it will be understood that when the wrench is to be engaged with the pipe the handle proper is first rotated to the right with respect to the bars 10 and 12, the handle proper will turn in the collar 22^a, during which time the screw-rod 21 will be forced from the handle, this movement serving to carry the slide, with its movable jaw, in the direction of the fixed jaw until the proper 100 spaced relation of the jaws is obtained. The jaws are then forced over the pipe, when the pressure of the pipe against the lower jaw rocks it on the pivot 20, connecting the slide with the rod 21, so as to carry the dog 17 into 105 engagement with the corresponding tooth of the ratchet-bar 10. This movement of

the slide carries the movable jaw to lie at an angle to the fixed jaw, so that the pipe may become firmly wedged between the jaws as the lower end of the wrench is swung to rotate the pipe. When the wrench is to be released from the pipe, as preparatory to taking a new hold, a slight rotation of the handle member 14 to the left causes the screw-rod 21 to pass part way into the member 14, so that a retrograde movement is given the slide and the movable jaw with respect to the fixed jaw, so that the pipe is instantly released.

To take a new hold, the handle member 14 is then turned the same angular distance to the right, and the pipe is then further rotated by means of the wrench.

What is claimed as the invention is—

1. The combination of the handle-bars 20 consisting of the rack-bar and the guide-bar and a fixed jaw carried thereby, of the slide, its jaw and dog, the latter being adapted to engage the teeth of the rack-bar, the handle and its feed-screw, projections on the sides of 25 the slide, and a pivot connecting the said projections with the handle between said bars.

2. The combination with the slide-bar and the rack-bar, of the fixed jaw carried by said bars, a slide and its bar movable on said bars, 30 a dog on the slide adapted to engage the teeth of the said rack-bar, the handle, and the screw feed-rod extended therethrough and pivotally connected with the said slide.

3. The combination with the slide-bar and 35 the rack-bar, of the fixed jaw carried by said bars, a slide and its bar movable on said bars, a dog on the slide adapted to engage the

teeth of the said rack-bar, the handle, and the screw feed-rod extended therethrough and pivotally connected with the said slide, an enlargement on the said bars, a nut on said screw feed-rod above said handle and the handle below it, and a set-screw adapted to fix said nut to said rod. 40

4. The combination with a fixed jaw and 45 its bar, an adjustable jaw and a slide upon which it is pivotally mounted, a rack-bar for the adjustable jaw, a dog on the slide to engage the rack-teeth of the rack-bar, a handle, a screw feed-rod controlled thereby and connected with the bar of the fixed jaw whereby 50 the latter may be moved or adjusted with respect to the adjustable jaw.

5. A pipe-wrench comprising a rack-bar 55 having a fixed jaw, a slide movable longitudinally of the rack-bar toward and away from the fixed jaw and having a jaw for coöperation with the fixed jaw, said slide having a dog arranged to engage the rack-bar at times, a handle member rotatably connected with 60 the rack-bar, a screw engaged with the handle member and pivotally connected with the slide, said slide being movable upon its pivot into and out of engagement with the rack-bar and the screw being movable into and 65 out of the handle member when the latter is rotated.

In testimony whereof I affix my signature in presence of two witnesses.
